(57) **CLAIM**

The ornamental design for a tape measurer, as shown and described.

DESCRIPTION

FIG. 1 is a top, front, left side perspective view of the tape measurer of the present invention;

FIG. 2 is a front elevational view of the tape measurer of FIG. 1;

FIG. 3 is a rear elevational view of the tape measurer of FIG. 1;

FIG. 4 is a left side elevational view of the tape measurer of FIG. 1;

FIG. 5 is a right side elevational view of the tape measurer of FIG. 1;

FIG. 6 is a top plan view of the tape measurer of FIG. 1; and, FIG. 7 is a bottom plan view of the tape measurer of FIG. 1.

The broken lines showing of numbers in FIGS. 1 and 2 only are for illustrative purposes only and form no part of the claimed design.
